UNITED STATES PATENT OFFICE

131,029

DESIGN FOR A TOOL CASE

William Emmett Russell, North Hollywood, Calif.

Application March 3, 1941, Serial No. 99,338

Term of patent 7 years

To all whom it may concern:

Be it known that I, William Emmett Russell, a citizen of the United States, residing at North Hollywood, in the county of Los Angeles and State of California, have invented a new, original, and ornamental Design for a Tool Case, of which the following is a specification, reference being had to the accompanying drawing, forming part thereof.

Fig. 1 is a top plan view of a tool case showing my new design.

Fig. 2 is a front view in elevation.

Fig. 3 is a side elevational view.

Fig. 4 is a rear elevational view.

I claim:

The ornamental design for a tool case, as shown.

WILLIAM EMMETT RUSSELL.
